CLAIM

The ornamental design for a gangway section of a railway vehicle, as shown and described.

DESCRIPTION

FIG. 1 is a left front perspective view of a gangway section of a railway vehicle showing my new design;
FIG. 2 is a right front perspective view thereof;
FIG. 3 is an upper left rear perspective view thereof;
FIG. 4 is a top view thereof;
FIG. 5 is a front view thereof; and,
FIG. 6 is a rear view thereof.

The broken line showings of FIGS. 1-6 are environmental only and not part of the claimed design.
